UNITED STATES PATENT OFFICE

96,821

DESIGN FOR A CARRYING CASE OR SIMILAR ARTICLE

Ernest A. de Graff, Chicago, Ill.

Application December 5, 1934, Serial No. 54,289

Term of patent 3½ years

To all whom it may concern:

Be it known that I, Ernest A. de Graff, a citizen of the United States of America, residing at Chicago, in the county of Cook and State of Illinois, have invented a new, original, and ornamental Design for a Carrying Case or Similar Article, of which the following is a specification, reference being had to the accompanying drawing, forming a part thereof.

In the drawing:

Fig. 1 is a view in perspective of the carrying case or similar article, showing the same closed and in upright standing position.

Fig. 2 is a view in perspective of the carrying case or similar article, showing the same in opened position.

The fine lines extending parallel to the margins of the vertical and horizontal areas of the stepped portions and the similar lines arranged in zig-zag fashion on the vertical face of the article, all indicate stepped or irregular borders along the specially shaped edges or corners of the carrying case.

I claim:

The ornamental design for a carrying case or similar article, substantially as shown and described.

Signed at Chicago, Cook County, Illinois, this sixth day of August, 1934.

ERNEST A. DE GRAFF.
